UNITED STATES PATENT OFFICE.

FRED MATHEWS, OF CHICAGO, ILLINOIS.

CARLINE.

1,396,703.

Specification of Letters Patent. Patented Nov. 8, 1921.

Application filed January 26, 1920. Serial No. 354,071.

To all whom it may concern:

Be it known that I, FRED MATHEWS, a citizen of the United States, residing at Chicago, in the county of Cook and State 5 of Illinois, have invented new and useful Improvements in Carlines, of which the following is a full, clear, and exact description.

My invention relates to the roofs of railroad cars and particularly to channeled carlines for the same, and its object is to strengthen and reinforce the ends of such channeled carlines, at which points the channels are deepest and where the roof load is supported. This I accomplish by a very 10 simple, inexpensive and effective addition to the ends of said carlines, substantially as hereinafter described and as particularly pointed out in the claims.

In the drawings:

20 Figure 1 is a side elevation of a broken away end of the carline showing my invention applied thereto.

Fig. 2 is a transverse section taken on dotted line 2, 2, Fig. 1, looking in the direction indicated by arrows.

Fig. 3 is a side view of the end of said carline showing a modified construction of my invention applied thereto.

Fig. 4 is a transverse section of the same 30 taken on dotted line 4, 4, Fig. 3, looking in the direction indicated by the arrows.

Fig. 5 is a plan view of said carline, showing yet another modification of my invention applied thereto.

Fig. 6 shows a transverse section taken on dotted line 6, 6, Fig. 5.

Fig. 7 is a longitudinal section of the same taken on dotted line 7, 7, Fig. 5.

Referring to the drawings A indicates a 40 broken away end of a channeled carline, in which the longitudinal channel therein is deepest at its ends. The longitudinal edges *a*, *a*, of this channel are flanged laterally and the end edges of the said carline are in 45 a vertical plane at right angles to the length of the same.

Each end of the carline is reinforced by an end-plate, which, as will hereinafter appear, has its vertical web *B* engaging the end 50 edges of the carline and closes the ends of the channel thereof. This vertical web is wider than the carline and its sides extend beyond the sides of the same. The upper edge of said web is bent horizontally over 55 the end of the carline and forms a flange *C*,

which laps over and is secured by rivets *c*, *c*, to the flanged edges *a*, of the channel of the carline, substantially as shown in the drawings. The lower edge of the vertical web *B* is extended and bent inward toward the center of the carline and is slit longitudinally to provide a central reach *D*, which laps under and is riveted to the bottom of the channel by a rivet *d*, and provides two struts *E*, *E*, that extend upward at a suitable angle from the lower edge of said web *B* alongside of each side of the channel to the underside of flanges *a*, *a*, to which latter they are secured by rivets *e*, *e*.

As thus constructed the ends of the carline 70 (which are the weakest of the structure) are greatly reinforced and strengthened, and are adapted to be supported either upon the top of the side walls (not shown) of a car or by securing the same to the inner vertical 75 surface of the same by means of rivets through the vertical web.

In Figs. 3 and 4 of the drawings, I show a modified construction of my invention. In this modification the channeled carline 80 *F* is constructed the same as the carline *A* illustrated in the first two figures of the drawings, but, the end-plate has its vertical web *G* extended down below the horizontal plane of the bottom of the channel of the 85 carline a suitable distance, and then bent upward and inward at, say, an angle of forty-five degrees, to form a strut *g*, that has its end *h* bent horizontally and made to bear flat against the underside of the channel, to which it is secured by rivet *k* or otherwise. The upper edge of the vertical web *G* of said modified end-plate is bent toward the center of the carline to form a flange *H* that laps over and is secured to the 90 flanged edge *f* of the channel by rivets *j* in the same manner as in the preferred form of my invention.

In Figs. 5, 6, and 7, of the drawings, I illustrate yet another modification of my 100 invention. In this modification the ends of the carline are reinforced by an end-plate *7*, which is also greater in width than the width of said carline, and has its vertical web transverse to and engaging the end edges 105 of the same. This plate *7* has an upper flange *9*, similar to the end-plates in both of the constructions hereinbefore described, which overlaps flanges *6*, *6*, of the end of the channel and is fastened thereto by means 110

of rivets 8, 8. Said plate 7, also has a lower flange 10 that projects to a greater extent than the upper flange 9, and engages the under side of the end of said channel. This lower flange 10 is preferably, gusset-shaped, that is, has its side edges extend obliquely from plate 7 in toward the center of the carline until they reach the underside of its channel, to which latter it is secured, preferably, by a rivet 12, placed midway between the vertical plane of the sides of said channel. This construction gives flange 10 of the end-plate a comparatively large superficial area that is adapted to rest upon the top of the side wall of the car (not shown).

What I claim as new is:

1. The combination with a channeled carline, of an end-plate engaging the end edges 20 of said carline and secured thereto, said plate being greater in width than the carline and having its ends extending laterally beyond the sides of the same, and provided with an inwardly extending flange which laps under and is secured to the bottom of the channel of said carline.
2. The combination with a channeled carline, of a transverse end-plate engaging and secured to the end edges of the same and 30 having upper and lower flanges, the upper flange lapping over and secured to the laterally flanged edges of the channel of said carline, and the lower flange lapping under and secured to the bottom of said carline.
3. The combination with a channeled carline, of a transverse plate, the vertical web 35 of which engages the end edges of said carline and which web is provided with an upper flange that laps over and is secured at its medial portion to the laterally flanged edges of the channel of the carline, and with a lower flange that laps under and is secured at its medial portion to the bottom of the said carline.
4. The combination with a channeled carline, of a transverse end-plate the length of 45 which exceeds the width of the carline, and the end edges of which latter it engages, said end-plate having an upper and a lower flange, the upper flange being narrower than the lower flange and lapping over and riveted to the flanged edges of the channel of said carline and the lower flange lapping under and secured to the bottom of said carline.
5. The combination with a channeled carline, of a transverse end-plate engaging and 50 secured to one of the ends of the same, said plate having a gusset-shaped flange extending inward from its lower edge and secured 60

at its medial portion to the bottom of the channel of the carline.

6. The combination with a channeled carline, of a transverse plate, the vertical web of which engages the end edges of said carline and which is provided with an upper flange that laps over and is secured at its medial portion to the laterally flanged edges of the channel of the carline, and with a lower gusset-shaped flange that laps under 65 and is secured at its medial portion to the bottom of the said carline.

7. The combination with a channeled carline of a transverse end-plate the vertical web of which engages the end edges of said 70 carline and extends down below the underside of the same and is then bent upward and inward and secured to the under side of the channel of said carline.

8. The combination with a carline, which 80 is channeled longitudinally, of a transverse plate the vertical web of which engages the end edges of said carline and has its upper edge flanged over and secured to the longitudinal flanges of the channel of said carline and its lower edge extended and formed into a strut that extends upward at an angle to the said carline to which it is secured.

9. The combination with a carline, which 90 is channeled longitudinally, of a transverse plate the vertical web of which engages the end edges of the carline and has its upper edge flanged over and secured to the transverse flanges of the longitudinal edges of 95 said carline, and has its lower edge extended and slit to provide struts that extend at an angle upward toward the center of the carline and engage and are secured to the flanges of said channel.

10. The combination with a carline which 100 is channeled longitudinally, of a transverse plate the vertical web of which engages the end edges of the carline and has its upper edge flanged over and secured to the transverse flanges of the longitudinal edges of 105 said carline, and has its lower edge extended and slit to provide a central horizontal member that is secured to the under side of the channel, and struts that extend at an angle upward toward the center of the carline and engage and are secured to the flanges of the same.

In witness whereof, I have hereunto set my hand and seal this 19th day of January, 1920.

FRED MATHEWS.
